UNITED STATES PATENT OFFICE.

LESLIE O. WETHERELL, OF ATTLEBORO, MASSACHUSETTS, ASSIGNOR TO FREEMAN-DAUGHADAY COMPANY, OF CHARTLEY, MASSACHUSETTS, A CORPORATION OF MASSACHUSETTS.

DISPLAY DEVICE.

Application filed December 19, 1922. Serial No. 607,861.

To all whom it may concern:

Be it known that I, LESLIE O. WETHERELL, a citizen of the United States, residing at Attleboro, in the county of Bristol and State of Massachusetts, have invented certain new and useful Improvements in Display Devices, of which the following is a specification.

This invention relates to display devices 10 of the class adapted for use in displaying articles of jewelry such as cuff buttons and the like, and the object of this invention is to provide a display device of this character in which individual cards or holders on 15 which articles of jewelry are mounted, are adapted to be removably held.

A further object of this invention is the provision of a holder card having its sides bent down to form resilient wings, the same 20 being adapted to be held in a receptacle having bearing walls whereby the inherent spring of the stock of the holder causes its side walls to expand and grip the sides of the receptacle to frictionally retain the 25 holder in operating position therein.

A still further object of the invention is the provision of such a display device having a front plate which is provided with openings with inturned resilient edge portions, which portions are adapted to receive 30 a receptacle in which the holder member is first mounted and to frictionally retain this box or receptacle therein.

With these and other objects in view, the 35 invention consists of certain novel features of construction, as will be more fully described, and particularly pointed out in the appended claims.

In the accompanying drawings,

40 Figure 1 is a front view of one form of my improved display device showing the front plate thereof as provided with a plurality of openings and in some of which openings the articles to be displayed are 45 mounted while from the other openings the articles and their mounts are removed to illustrate the marginal gripping flanges or flaps.

Figure 2 is a perspective view illustrating 50 the tray member of the display device having a front cover plate provided with a holder with a box therein, another showing the box without a holder and a third open-

ing showing the flaps alone with the box and holder removed. 55

Figure 3 is a sectional edge view showing a pair of cuff buttons mounted on a holder, the holder mounted in a box and the box mounted in an opening in the front plate and retained therein by the edge gripping 60 wing portions.

Figure 4 is a perspective view showing one of the cards or holder members removed.

Figure 5 is a sectional end view showing the holder member with a cuff button 65 mounted thereon.

Figure 6 is a perspective view of one of the boxes or receptacles in which a holder member carrying a pair of cuff buttons is mounted. 70

Figure 7 is a perspective view illustrating another form of display device provided with channel openings for the reception of my improved holder members which may be retained therein by the frictional gripping 75 surface of its side walls.

It is found in practice of advantage in some instances, in the mounting of jewelry such as cuff buttons and the like, for display, to mount a pair of buttons on a card 80 such as that illustrated in Figure 4, the same having rearwardly bent or turned side edges arranged to retain their inherent spring or opening tension, and to provide a receptacle for such a holder in which the holder is held 85 by friction of its side wings or walls.

It is also found of advantage to provide a display card having a tray-shaped back plate with a front cover plate provided with spaced-apart openings for the reception and 90 display of a plurality of cuff buttons and so formed that the holder members for the buttons may be readily positioned in the openings in the display device and retained 95 therein by friction to be readily removed as desired, and the following is a detailed description of one means by which these results may be accomplished:

With reference to the drawings, 10 designates a back plate for my improved display 100 device which is preferably in the form of a tray having side walls 11 and end walls 12, to the outturned edges of which is secured a front cover plate 14. This front plate is preferably provided with a plurality of 105 spaced apart openings 15, each opening be-

ing formed by cutting or slitting a portion of the stock and turning inwardly these marginal portions to form spring-gripping flaps about its edge.

In some cases the flaps or wings 16 may be formed along the sides of the openings while in other cases flaps 17 may be formed on the ends of the openings, while in other cases both side and end flaps may be provided, the stock of the plate at the bend being preferably creased and not secured so as to cause the flaps to retain the inherent spring of the stock, whereby these wings are caused to grip, bind and frictionally retain any article inserted to fit closely therein to be engaged by them.

In order to provide a simple and effective holder or carrier member on which to mount or attach a pair of separable cuff buttons or other article, I have formed a card 18 which may be formed of any suitable material but which is preferably formed of cardboard as illustrated in Figure 4, having its side edges 19 bent rearwardly from the plane of its face forming the same into substantially U-shape in cross section. These wings or sides are preferably creased but not scored at the line on which they are folded, whereby they retain the inherent spring of the stock causing them to spring outwardly or away from each other.

The outer face of this holder member is preferably provided with a pair of openings 20 through which cuff buttons 21 are mounted, and the depth of the wings or sides is substantially that of the length of one-half of the button.

It is also found of advantage to provide a small box 22 as best shown in Figure 6, of a length and depth substantially that of the holder, whereby these side wings 19 of the holder may be pressed inwardly towards each other to enter the box and when positioned in the box they will spring outwardly and grip the side walls thereof to be frictionally retained therein.

It is also found of advantage to mount the boxes containing the cuff buttons, in the openings 15 in the front plate of the display device, whereby the marginal edge flaps of the opening into which it is set will serve to frictionally grip and retain the box therein; by which construction the box may be readily removed from the opening in the front plate carrying the cuff buttons therein and the holder with the buttons may be readily removed from the box when desired and may be readily replaced in the box when sold and delivered.

In some instances instead of forming the front plate with a plurality of openings therein, an elongated groove such as that shown at 23 in the modified construction in Figure 7, may be employed in which the holders may be mounted directly in and fric-

tionally retained by the inherent spring of their side walls or wings thereby gripping the side walls of the groove.

My improved display device is very handsome and attractive in appearance and when the boxes and the holders are positioned therein their faces are flush with the plane of the front plate, and by the use of this device the goods may be mounted in their holders and the holders retained by friction in display position to be readily removed for inspection or for sale when desired.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A display device for removably mounting a multiplicity of articles of jewelry, comprising a receptacle, a front plate for said receptacle having a series of openings with folded-down side bearing walls of a substantial depth, a plurality of article carriers each adapted to have its article attached thereto, said carriers being substantially U-shape in cross section and having resilient side walls of a depth substantially that of said receptacle, the front face of each carrier lying in substantially the same plane as that of said front plate, the walls of said carrier and opening springing relatively toward each other to grip and frictionally retain the carrier with the article attached thereto in said plate.

2. In a display device, a plate provided with a plurality of openings, a box-shaped receptacle in each opening, an article holder in each receptacle formed substantially U-shape in cross section, the side walls of said holder gripping the walls of the box by the inherent spring of its stock to frictionally retain the holder therein.

3. In a display device, a plurality of box-shaped receptacles, article holders formed substantially U-shape in cross section, the side walls of said holders being adapted to enter and grip the walls of the boxes by the inherent spring of the stock to frictionally retain the holder therein, and the front plate of said display device being provided with a plurality of openings for the reception of said boxes, and each opening having means for retaining one of said boxes therein.

4. In a display device having a front plate, a box shaped receptacle, an article holder therein formed substantially U-shape in cross section the side walls of said holder having an inherently outward spring to grip the walls of the receptacle to frictionally retain the holder therein, said front plate being provided with openings having resilient

edge members for gripping the sides of the box and frictionally retaining it therein.

5. A display device comprising a tray-shaped back plate, a front cover plate for the tray, said front plate having openings with inturned resilient edge walls, a box-shaped receptacle inserted into each of said openings in said front plate to be frictionally

retained therein by the grip of its edge walls, and an article holder formed substantially 10 U-shape in cross section with outwardly springing side walls inserted into said box to grip its walls to be frictionally retained therein.

In testimony whereof I affix my signature.
LESLIE O. WETHERELL.
